DUAL GASOLINE DISPENSING PUMP

Edward D. Rapisarda, Agawam, Mass., assignor to Gilbert & Barker Manufacturing Company, West Springfield, Mass., a corporation of Massachusetts

Application May 1, 1957, Serial No. 45,969

Term of patent 14 years

(Cl. D52—2)

FIG. 1

FIG. 2

FIG. 3

Fig. 1 is a top plan view of a dual gasoline dispensing pump embodying my new design;

Fig. 2 is a front elevational view of the pump; and

Fig. 3 is a side elevational view of the pump.

The front and rear of the pump and both sides of the pump are the same in appearance.

The dominant features of the design reside in the portion shown in full lines.

Some of the broken line portions as seen on the sides of the pump in Fig. 2 have been omitted from the other figures for convenience of illustration.

1 claim:

The ornamental design for a dual gasoline dispensing pump, as shown and described.
